CATHODE RAY DEVICE

Harold J. McCreary, Chicago, Ill., assignor of one-fourth to Rodney G. Richardson, one-fourth to Henry Hugo Engelhardt, and one-fourth to Forrest B. Brunner, all of Chicago, Ill.

Application January 15, 1931, Serial No. 508,932

18 Claims. (Cl. 33—204)

My invention relates in general to cathode ray devices, and more in particular to a cathode ray device in which use is made of the deflection of the cathode ray or beam by an external field. A special object of the invention is a cathode ray device in which the cathode ray is deflected by the earth's magnetic field, the device operating as a compass or direction indicator.

One embodiment of my invention, which may be termed a cathode ray compass, is illustrated in the accompanying drawing, comprising Figs. 1, 2, and 3. Fig. 1 is a plan view, partly in section, showing the mechanical construction of the compass, Fig. 2 is a diagrammatic drawing of the electrical circuits involved, while Fig. 3 is a fragmentary drawing showing the method of suspending the cathode ray tube, a detail which does not appear from Fig. 1.

Referring to Fig. 1, the reference character indicates a base which may be of wood or other suitable material. Mounted on the base 1 is a bearing member 3. The reference character 5 indicates a platform, which is secured to a hub 6, the lower end of which is formed into a shaft 4. Suitable roller and ball bearings are provided between the shaft 4 and the bearing member 3. Thus the platform 5 is supported for rotation on the base 1. A motor 23 is adapted to rotate the platform 5 by means of a worm 18 and a spur gear 7, the latter of which is secured to the hub 6.

Mounted on the platform 5 are two upright standards 8 and 9, Figs. 1 and 3. The cathode ray tube 20 is pivotally supported at the upper end of these standards. By reference to Fig. 3, it will be seen that the tube 20 is held in a ring or band 10. The ring 10 has two laterally extending shafts 11 and 12 which pass through bearings in the standards 9 and 8, respectively.

The reference character 21 indicates the elevating motor. By means of gears 17 and 16 this motor is able to rotate the vertical shaft 15, held in suitable bearings projecting from standard 8. Shaft 15 carries a worm 14 which meshes with the spur gear 13. The latter is secured to shaft 12, from which it will be evident that rotation of the gear will rotate the band 10 to elevate or lower the upper end of the cathode ray tube 20 depending on the direction of rotation.

Referring to Fig. 2, the cathode ray tube 20 comprises a glass envelope, a hot cathode 30, a perforated shield 31, an anode 32, and a plate or target 35 against which the cathode ray impinges. In general the cathode ray tube may be of the usual construction. It is desirable, how-

ever, to make the openings in the shield 31 and anode 32 larger than usual so as to secure a good sized ray or beam. With an opening one fourth inch in diameter a ray carrying one milliampere can be obtained. The target 35 is suitably secured in the end of the tube opposite the cathode. This target comprises four segments, 36, 37, 38, and 39, which are insulated from each other. Each segment has a separate terminal wire extending outside the tube.

For the purpose of controlling the elevating motor 21 there is provided a polar relay 40 and relays 46 and 47. The rotating motor 23 is controlled by means of a polar relay 60 and relays 64 and 65. Current is supplied by batteries B, B¹, and B².

The necessary circuit connections between the base and the apparatus mounted on the rotatable platform 5 are taken through slip rings and brushes, so as to permit unlimited rotation of the platform. Referring to Fig. 1, a cylindrical block of insulating material 25 encircles the bearing member 3 and has embedded in its surface a series of slip rings 26. A brush holder 28 is secured to the gear 7, and carries a series of spring actuated brushes 27 which bear on the rings 26. An opening 84 drilled in the block 25 permits conductors to be connected to the slip rings 26. These conductors may be taken through a conduit 83 to the box 24. This latter may contain the batteries and the relays 60, 64, and 65. It also serves as a support for the motor 23. Suitable conduits such as 80, 81, and 82 may also be provided for protecting the conductors leading to and connecting together the apparatus mounted on the platform 5. The box 22 contains the relays 40, 46, and 47.

The conductors connecting to the tube 20 are taken through conduit 81 and are preferably flexible leads which extend from the end of the conduit to the terminals of the tube. These leads should be long enough to provide for a considerable range of movement of the tube. It may be pointed out that the compass herein described specifically is not intended to provide for an unlimited movement of the tube about a horizontal axis because in most commercial uses, such as on ships or airplanes, such movement is not required. In certain cases, however, as in the case of a military or stunt plane, an unlimited rotation of the tube about its horizontal axis may have to be provided for. This can readily be done by using a system of brushes and slip rings, such as are shown for carrying the electrical connections between the platform and the base.

The operation of the cathode ray tube in producing the cathode ray needs no extended explanation. Current for heating the cathode 30 is supplied by battery B, which is connected by a 5 pair of slip rings and brushed to conductors 56 and 57. These conductors also supply current from battery B for operating relays 46, 47, 64, and 65, and the motors 21 and 23. The proper accelerating potential is supplied to the anode 32 by battery B¹, which is connected through a slip ring and brush to conductor 58. The standards 8 and 9 and other parts near the cathode ray tube should be made of non-magnetic material.

The operation of the compass will now be described, it being assumed that the device is mounted in an airplane. The base 1 is suitably secured in the cockpit of the plane in a horizontal position, and the circuits are connected up as shown in Fig. 2. It may be pointed out now that 15 the principle of operation is to maintain the cathode ray beam parallel to the lines of force of the earth's magnetic field. This is accomplished by rotating the platform 5 or by changing the elevation of the tube 20, or both, depending on 20 the movement of the plane.

The operation will be explained herein on the assumption that it is desired to have the end of the tube containing the target point to the south, the cathode end pointing to the north. In the 30 northern hemisphere the lines of force of the earth's field make an angle with the surface of the earth the apex of which is toward the north. The amount of the angle, of course, depends on the latitude. The position of the tube, therefore, will be somewhat as shown in Figs. 2 and 3, the exact angle of inclination depending on the 35 latitude of the plane.

For convenience it may be assumed that the plane is traveling due south. The tube points 40 south and the cathode ray, which is parallel to the earth's field, impinges on the center of the target 35. This is the normal position of the beam. If the beam is small enough it will impinge on insulating material at the center of the 45 target and little or no current will flow through relays 40 and 60. However, the beam may be large enough to impinge simultaneously on segments 36, 37, 38, and 39 of the target, but this produces no effect because the relays 40 and 60 50 are differentially wound as will appear presently.

Suppose now that the plane noses down toward the earth. This causes the cathode ray to cut the earth's field, with the result that it is deflected to the right and impinges equally on segments 55 37 and 38 at some distance from the center of the target. A circuit is thus established which includes the cathode 30, cathode ray, segments 37 and 38, windings 42 and 43 of polar relay 40 in parallel, conductors 54 and 55 in parallel, brushes 60 27, slip rings 26, windings 61 and 62 of polar relay 60 in parallel, and the batteries B² and B¹ in series. The windings 61 and 62 of relay 60 65 oppose each other and the relay is not operated. Windings 42 and 43 of polar relay 40 assist each other and the relay is operated to close a circuit for relay 46 in an obvious manner by means of armature 45. Upon energizing relay 46 closes a circuit for the armature winding of motor 21 at armature 50, and at armatures 48 and 49 it closes a circuit for the field winding of the motor. The motor 21, therefore, starts up and rotates in such a direction as to elevate the target end of the tube. As the tube is elevated the point at which the cathode ray impinges the target moves back to 70 ward the center of the target. When the tube is 75

once more parallel to the earth's field the point of contact with the target will be at the center and relay 40 will release its armature. This breaks the circuit of relay 46 which deenergizes and stops the motor 21.

Suppose now that the plane noses upward. This deflects the beam to the left, causing it to impinge on segments 36 and 39. A circuit is thus established which includes segments 36 and 39, and windings 44 and 41 of polar relay 40, the 10 remaining elements of the circuit being the same as previously explained. Relay 60 remains inactive as before, but relay 40 is operated, its armature 45 being attracted in the opposite direction from what formerly was the case, however. A circuit is thus closed for relay 47, which at armature 53 closes a circuit for the armature winding of motor 21 and at armatures 51 and 52 closes a circuit for the field winding of the motor. The field is connected up reversed and the motor 20 now runs in the proper direction to lower the target end of the tube. When the necessary correction is made the ray will once more contact the target at the center, the relays 40 and 47 will fall away and the motor 21 will stop.

It will now be assumed that the plane turns to the left. As a result the cathode ray is deflected downward, so that it impinges on segments 38 and 39. A circuit is, therefore, established which includes the cathode 30, the cathode ray, the 30 segments 38 and 39, windings 42 and 41 of polar relay 40 in parallel, conductor 54, a brush 27 and a slip ring 26, winding 61 of polar relay 60, and batteries B² and B¹. Windings 41 and 42 of polar relay 40 oppose each other and relay 40 is not operated. Relay 60 is operated and its armature 63 closes a circuit for relay 64, which in turn closes circuits for the armature and field windings of motor 23. The motor now starts up and rotates the platform 5 in such a direction as to turn 40 the tube 20 to the right, thereby bringing the tube back parallel to the earth's field. The point of contact with the target moves up to the center of the target, relays 60 and 64 are deenergized, and motor 23 stops.

If we assume now that the plane turns to the right, the cathode ray will be deflected upward and will impinge on segments 36 and 37. This establishes a circuit similar to the one previously traced except that it includes windings 43 and 44 of relay 40 and winding 62 of relay 60. Relay 40 does not operate because windings 43 and 44 oppose each other. Relay 60 operates and now closes a circuit for relay 65. The latter relay starts the motor 23, but since the field is connected up reversed, the motor runs in the opposite direction from what was the case before, and turns the platform 5 in a counter-clockwise direction so as to turn the end of the tube 20 to the left. When the necessary correction has been made the ray 60 will once more engage the center of the target, and relays 60 and 65 will deenergize to stop the motor.

In the foregoing, simple movements of the plane have been considered for convenience in explaining the operations which take place in maintaining the axis of the tube parallel to the earth's field. It will be clear, however, especially in the case of an air plane, that compound directional changes may take place. For instance, 70 the plane may nose downward and at the same time turn to the left. This causes the cathode ray to impinge on segment 38. A circuit is thus established which includes winding 42 of polar relay 40 and winding 61 of polar relay 60. By the 75

operation of these two relays, motors 21 and 23 are operated simultaneously to increase the elevation of the tube and rotate it to the right. If the vertical and horizontal directional changes were equal the point of contact of the beam with the target will move back along a radius of the target toward the center. In case the change of direction to the left was relatively small, however, the correction for this change will be accomplished first and the point of contact with the target will be brought to the dividing line between segments 37 and 38. Segment 37 is now rendered active, as well as, segment 38. As a result winding 43 of relay 40 and winding 62 of relay 60 are included in the circuit. This deenergizes relay 60 to stop the motor 23, but relay 40 remains energized and motor 21 continues running until the beam reaches the center of the target.

The operations which take place in the event of other changes in direction may readily be deduced from the foregoing and it will be unnecessary to further extend the explanation. Suffice it to say that the axis of the tube is maintained parallel to the lines of force of the earth's field at all times, except for momentary displacements which take place when the plane changes direction, which are promptly corrected for.

Since the tube points in one direction continually, that is, to the south, it constitutes a compass or direction indicator. The direction in which the plane is traveling may be noted directly by observing the position of the tube, and in some cases this is accurate enough. If desired, however, the entire apparatus may be enclosed in a container having a dial forming the top thereof. A forked shaft may be secured to the standards 8 and 9 and extend upward through the cover of the container at the center of the dial. This arrangement will give a more accurate reading and at the same time the parts will be protected from injury. The dial and pointer may also be located at some distance from the apparatus with a shaft and gears connecting the pointer with the shaft 4 so that the two will move in synchronism.

It will be apparent that in some situations the compass will not require an elevating mechanism. When the only directional changes which take place are such as can be corrected for by rotation of the device, the segments 36 and 37 may be united, as are segments 38 and 39. The resulting half discs are connected directly to a polar relay such as 60, relay 40 and the associated apparatus being omitted. It may be noted also that the apparatus may be used to measure the inclination of the lines of force of the earth's field to the surface of the earth at any point. Other modifications and uses are within the scope of the invention.

I do not wish to be limited, therefore, to the precise structure shown and described herein but desire to secure by Letters Patent all forms and modifications of my invention which are covered by the appended claims.

I claim:

1. In a compass, means for producing a cathode ray, a movable member, and means controlled by the ray for maintaining said member parallel to the lines of force of the earth's field, said last means including mechanism for moving said member to correct for angular displacement in both vertical and horizontal planes.
2. In a compass, a cathode ray tube, and means for automatically maintaining the axis of said tube parallel to the lines of force of the earth's

field, said means comprising mechanism responsive to deflection of the ray when it cuts the field.

3. In a compass, a support, a cathode ray tube mounted on said support, means for moving the tube relative to said support in two different planes, and circuits including said ray and established responsive to deflection of the ray when the position of the support is altered relative to a magnetic field for controlling said moving means to maintain the said tube in fixed relation to said field.

4. In combination, a cathode ray tube having its axis normally in a given position, and means responsive to the deflection of the ray by a field of force when the position of the tube is changed relative to said field for restoring said tube to its original position.

5. In combination, a cathode ray tube, a circuit completed by deflection of the ray by a field of force when the tube is moved in a direction such that the ray cuts said field, and means controlled over said circuit for moving the tube in another direction.

6. In combination, apparatus for generating a cathode ray and located in a magnetic field, a circuit completed by deflection of the ray when the position of said apparatus relative to the field is changed, and means controlled over said circuit for restoring said apparatus to its initial position.

7. An instrument comprising means for generating a cathode ray, a reference member, a member angularly movable with respect to said reference member, and means responsive to deflection of said ray when subjected to the earth's field for positioning said second member to indicate the inclination of the earth's field with respect to said reference member.

8. An instrument comprising means for generating a cathode ray, a movable member, means for positioning said member at different angles to the surface of the earth, and means responsive to deflection of said ray when influenced by the earth's field for controlling said positioning means.

9. A climb and dive indicator for aircraft, for use on courses which are not substantially normal to the lines of force of the earth's field, said indicator comprising indicating means, means for producing a cathode ray, means for operating said indicating means, and means including a circuit completed by deflection of the cathode ray by the earth's field for controlling said operating means.

10. A compass for indicating direction toward or away from the surface of the earth, said compass comprising a movable member, means for moving said member to maintain it at a known angle to the earth's surface, means for producing a cathode ray, and means controlled by said cathode ray due to a change in its position in the earth's field for controlling said moving means.

11. A compound compass for indicating direction in two different planes, said compass comprising a cathode ray tube, means for positioning said tube in both said planes, and means responsive to deflection of the ray by the earth's field for controlling said positioning means to restore the ray to undeflected position.

12. An instrument comprising a cathode ray tube, means for moving said tube in two different planes, and means responsive to deflection of the ray by an external field for controlling said moving means.

13. In combination, a support, a cathode ray tube rotatably mounted on said support, rotating means for said tube, and means for operating said

rotating means responsive to deflection of said ray by a magnetic field.

14. In a compass, a main supporting member, a cathode ray tube mounted thereon, mechanism for moving said tube relative to said member, and means controlled by deflection of the ray when the compass is moved relative to the earth's field for operating said mechanism to restore the ray to undeflected position.
15. In combination, a cathode ray tube, a circuit completed by deflection of the ray by a field of force when the tube is moved in a direction such that the ray cuts said field, and means controlled over said circuit for producing further movement of said tube.

16. An instrument comprising means for generating a cathode ray, a horizontal member, a member movable about a horizontal axis, means for supporting said axis adjacent said horizontal member with the second member at a variable angle thereto depending on its position on said axis, and means responsive to deflection of said ray by the earth's magnetic field for moving said

second member on said axis to indicate the inclination of the earth's field with respect to said horizontal member.

17. An instrument comprising means for generating a cathode ray, a member angularly movable relative to the surface of the earth, and means controlled by deflection of said ray by the earth's field for positioning said member by angular movement thereof to indicate the inclination of the earth's field where the instrument is located.

18. In combination, apparatus for producing a cathode ray which is parallel to the lines of force in a magnetic field, said apparatus including a cathode ray tube, a circuit completed by deflection of the ray by said field responsive to a relative movement between the said tube and magnetic field such that the ray cuts the said field, and means controlled over said circuit for restoring the relation between the tube and field so that the latter is not cut by the ray.

HAROLD J. McCREARY.
